UNITED STATES PATENT OFFICE.

CHARLES D. ALLAN, OF CHICAGO, ILLINOIS.

COMBINATION KILN AND HEATER.

1,099,632.

Specification of Letters Patent.

Patented June 9, 1914.

Application filed December 26, 1913. Serial No. 808,784.

To all whom it may concern:

Be it known that I, CHARLES D. ALLAN, a citizen of the United States, and a resident of Chicago, in the county of Cook and State 5 of Illinois, have invented a certain new and useful Improvement in Combination Kilns and Heaters, of which the following is a specification.

My invention relates to kilns of the type 10 now in common use for burning or firing certain clay products.

In the manufacture of clay products, such as tiling of the kind largely used in lobbies, bath-rooms, vestibules, etc., the product is 15 first dried in kilns of the tunnel type, or specially constructed drying rooms, these kilns or rooms being heated by steam in coils or radiators. When the moisture has been driven off, the tile or other product is 20 packed in fire clay boxes known as "saggars" and these "saggars" are then placed in the kiln where the product contained therein is subjected to the direct heat produced by the furnaces which surround the 25 base of the kiln, and which operates to vitrify the contents of said "saggars" into the finished product.

When the kiln is started, it is cold and must be heated gradually and, during this 30 heating up period, the hot gases produced by combustion in the furnaces at the base of the kiln, are permitted to pass directly upward through the kiln and to escape through openings in the inner crown or roof thereof. 35 After the kiln is thoroughly heated up, the openings in the inner crown of the kiln are closed by means of dampers provided for the purpose, which forces the hot gases downward and out through openings in the 40 floor of the kiln, whence they pass under the floor of the kiln to openings formed in the base of the central stack of the kiln through which they are discharged into the space between the inner and the outer crowns, and 45 from thence into the atmosphere. As at present constructed, said stack terminates flush with the top of the inner crown of the kiln, and is controlled by means of a suitable damper provided for the purpose.

50 A kiln burning usually requires about 72 hours, during which time the fuel equivalent of from 400,000 to 500,000 cubic feet of natural gas is consumed, having a heat value of about 900 B. T. U. per cubic foot, 55 the rate of combustion increasing from a small amount, during the time the kiln, with

its contents, is being heated up, to a gas consumption of 7000 cubic feet per hour during the last 24 hours, having a heat value of 6,300,000 B. T. U. per hour, or 60 approximately 200 boiler horse power. After the kiln is heated to a desired temperature, 65 the process being only partially, if at all, chemically endothermic in character, it follows that a great percentage of the heat, 70 probably 50% or more, passes out through the top of the kiln and is wasted, no satisfactory method of using this heat having yet been found of which I have any knowledge. 75

The object of the present invention is to provide means in combination with a kiln of the general type described, whereby this waste heat can be utilized for the initial drying of the product or for other purposes, 75 preferably through the medium of a system of hot water heating under forced circulation.

To effect this object a device of my invention comprises the various features, combinations of features and detail of construction hereinafter described and claimed.

In the accompanying drawings in which my invention is fully illustrated, Figure 1 is a vertical, central, sectional view of a combined kiln and heater of my invention. Fig. 2 is a sectional plan view thereof on the line 2-2 of Fig. 1; and Fig. 3 is a sectional plan view thereof on the line 3-3 of Fig. 1.

As shown in the drawings, my improved 90 water heater is shown in combination with a kiln of the familiar type comprising a chamber A formed by side walls A¹, an inner crown or roof A², and a floor A³; upper chamber B, the side walls B¹ of which 95 form an extension of the side walls A¹ of the chamber A, and which converge upwardly. The top of the chamber B is open to permit the products of combustion which enter said chamber B from the chamber A to escape 100 freely into the atmosphere. Both the chambers A and B are preferably circular in cross section. Heat is adapted to be supplied to the kiln by furnaces C arranged around the base of the kiln and which communicate directly with the lower chamber A of the kiln through flues or openings c at the inner ends thereof.

Formed in the inner crown or roof A² of the chamber A are holes or openings a, 110 which are adapted to be closed by removable dampers or covers a¹, holes a² being formed

in the walls B^1 to provide access to said dampers, and formed in the floor of said chamber A are holes or openings a^3 which connect said chamber A with a chamber a^4 located below the floor of the chamber A and which communicates with a vertical stack A^4 concentric with chamber A by means of openings a^5 formed in the base of said stack A^4 . When the holes or openings a in the inner crown A^2 of the chamber A are open, the products of combustion will pass directly from said chamber A through said holes or openings into the chamber B, whence they will escape through the open upper end of said chamber B into the atmosphere. When the holes or openings a in the inner crown A^2 of the chamber A are closed, the products of combustion will pass downwardly through the holes or openings a^3 in the floor of the chamber A into the chamber a^4 , thence through the openings a^5 into the stack A^4 , upwardly through said stack into the chamber B and out through the open end of said chamber B as before. As heretofore constructed, the vertical central stack A^4 has terminated substantially flush with the top of the inner crown A^2 , and the chamber B has been entirely vacant. As regarding its usual features, and excepting as hereinafter particularly described, the kiln shown in the drawings conforms to the foregoing type and will be readily understood by persons familiar with the art without a further detailed description thereof.

In accordance with my invention, the stack A^4 is extended a considerable distance above the inner crown A^2 of the chamber A, as shown at 1, and communication between the interior of the stack A^4 and the interior of the chamber B is controlled by a damper 2 carried at the inner end of a lever 3 pivoted at 4 in an opening 5 formed in the wall B^1 of the chamber B.

Supported on a suitable foundation within the chamber B and surrounding the stack extension 1 in said chamber is a heater, designated as a whole D, and which consists of inner and outer shells 6 and 7, and tubes 8 arranged in the space between said shells 6 and 7 the ends of which tubes are secured in heads or tube sheets 9 and 10 which close the space between said shells 6 and 7 in which the tubes 8 are located.

Formed at the lower end of the heater D below the tube sheet 10 is a chamber 11 which is in open communication with the lower ends of the tubes 8 and which chamber 11 communicates with the interior of the stack A^4 and its extension 1 by means of openings 12 formed in said stack A^4 or its extension 1. Communication between the interior of the stack A^4 and the lower ends of the tubes 8, through the openings 12 and the chamber 11 is controlled by an annular louver damper 13 which divides said cham-

ber 11 into upper and lower compartments, the upper compartment communicating directly with the tubes 8 and the lower compartment with the stack openings 12. As shown, see particularly Fig. 3, the damper openings are shown in open position in full lines and in closed position in dotted lines. As shown, the chamber 11 is formed partly by the lower ends of the inner and outer shells 6 and 7, which extend somewhat below the lower tube sheet 10, and partly by the setting or foundation 14 for said heater, on which the lower end of the outer shell 7 of the heater rests. Communicating with said heater D adjacent to its lower and upper ends, respectively, are an admission pipe 15 and a discharge pipe 16, which connect said heater to a hot water heating system, preferably of the forced circulation type.

In practice the method of operating a heater of my invention in combination with a kiln of the kind described is as follows: After the space A of the kiln is packed full of "saggars" containing the clay product to be burnt or fired, the furnaces C are lighted. When the kiln is first started and while it is being heated up, the hot waste gases of combustion from the furnaces C pass up through the chamber A and out through the openings a in the inner crown A^2 of said chamber A into the chamber B, and from the upper end of said chamber B into the outside atmosphere. After the kiln and its contents are thoroughly heated, the openings a in the inner crown A^2 and the damper 2 at the upper end of the stack A^4 are closed, and the annular louver damper 13 is open which will cause the hot waste gases of combustion to pass downwardly through the openings a^3 in the floor of the chamber A, through the chamber a^4 beneath said floor, through the openings a^5 into the stack A^4 , through the openings 12, through the chamber 11 upward through the tubes 8, through the upper end of the chamber B, and thence into the outside atmosphere.

It is obvious that if the circulating water of a system of hot water heating passes into the space in the heater D surrounding the tubes 8, through the inlet pipe 15 and out through the outlet pipe 16, at the same time that the hot waste gases of combustion are passing through the said tubes 8, that the said circulating water will be heated to a high degree. If the said circulating water should be heated to a temperature over and above that which is desired, then the damper 2 may be partly opened and the annular louver damper 13 partly closed to an extent that any part of the hot waste gases of combustion may be utilized for heating the circulating water and the balance may pass out to the atmosphere, thus securing regulation of the amount of heat imparted to the cir-

culating water through manipulation of the dampers 2 and 13. To prevent injury to the heater D from over heating when not in use, the inner shell 6 of said heater is preferably made somewhat larger than the extension 1 of the stack A⁴ and is spaced therefrom on all sides as shown at 17.

I claim:—

1. In combination with a kiln of the type described, an extension of the stack of the kiln above the inner crown thereof, a water heater comprising inner and outer shells which surround said stack extension, tubes in the space between said shells, tube sheets which inclose a space between said shells in which tube sheets the tubes are secured, said kiln and heater being provided with communication between the interior of the stack and the heater tubes, means for regulating the area of free opening of said communication, and means for regulating the free area of opening of stack above the line of communication of its interior with the tubes, substantially as described.
2. In combination with a kiln of the type described, an extension of the stack of the kiln above the inner crown thereof, a water heater comprising inner and outer shells which surround said stack extension, tubes in the space between said shells, tube sheets which inclose a space between said shells in which tube sheets the tubes are secured, a chamber at one end of said heater comprising separate communicating compartments,

one of which communicates with the heater 35 tubes and the other with the interior of the stack, means for regulating the area of free opening between the two compartments of said chamber, and means for regulating the area of free opening of the stack above the 40 point of its communication with the aforesaid chamber, substantially as described.

3. In combination with a kiln of the type described, an extension of the stack of the kiln above the inner crown thereof, a water 45 heater comprising inner and outer shells which surround said stack extension, the inner shell being larger than and being spaced from said stack extension, tubes in the space between said shells, tube sheets which inclose 50 a space between said shells in which tube sheets the tubes are secured, said kiln and heater being provided with communication between the interior of the stack and the heater tubes, means for regulating the area 55 of free opening of said communication, and means for regulating the area of free opening of stack above the line of communication of its interior with the tubes, substantially as described.

In testimony that I claim the foregoing as my invention, I affix my signature in the presence of two subscribing witnesses this 23rd day of December, 1913.

CHARLES D. ALLAN.
